UNITED STATES PATENT OFFICE.

AUGUST HOLMGREN, OF LAKE PARK, MINNESOTA.

PUNCHING-MACHINE.

No. 910,063.

Specification of Letters Patent.

Patented Jan. 19, 1909.

Application filed April 14, 1908. Serial No. 427,069.

To all whom it may concern:

Be it known that I, AUGUST HOLMGREN, a citizen of the United States, residing at Lake Park, in the county of Becker and 5 State of Minnesota, have invented certain new and useful Improvements in Punching-Machines; and I do hereby declare the following to be a full, clear, and exact description of the invention, such as will enable 10 others skilled in the art to which it appertains to make and use the same.

This invention relates to punching machines; and it consists in the novel construction and combination of the parts hereinabove 15 fully described and claimed.

In the drawings, Figure 1 is a side view of the punching machine. Fig. 2 is a front view of the machine. Fig. 3 is a sectional plan view, taken on the line $x-x$ in Fig. 1. 20 A is the frame of the machine provided with two parallel side bars a' having feet b at their bottoms and projections B at their upper ends.

C is a central bar for stiffening the frame, 25 secured between the middle parts of the bars a' and having no feet or projections.

D is a loop-shaped bracket for supporting the die-block or table E; and F is a loop-shaped guide for the punch. The forked 30 end portions of the bracket D and guide F are arranged to straddle the central bar C and to come between the side bars a' , and all the said parts are rigidly secured together by rivets e. When constructed in this manner the bars a' and C can be made of forged 35 or rolled metal, so that there is less liability of fracture than when the frame is made of cast iron. When a wrought iron frame is used the machine is also lighter and takes 40 up less room in shipment.

G is a crank for operating the punch. This crank is formed on a crankshaft g which is journaled in bearings b' on the 45 projections B. Plates c are provided for holding the said shaft in engagement with its bearings, and these plates are secured to the projections B.

H are arms secured to the crankshaft and 50 provided with notched quadrant-plates h . I is an operating-lever pivoted to the arms H by a pin h' . The lever I is provided with a retractable catch i for engaging with the

notches of the quadrant-plates, so that the lever can be set at any desired angle with the arms H.

55

J is a connecting-bar which is pivoted at its upper end to the crank G. The lower end of this bar is provided with a recessed socket j having a rounded bearing surface and having side flanges j' .

60

K is the punch provided with a stem k which is slidable in the guide F, and which has a rounded head k' at its upper end provided with a projection m .

L is a hook which is pivoted to the bar J 65 by a pin m' , and which engages with the projection m , so that the head k' is held in engagement with the socket j .

N is a die-block or table which rests on the bracket D and which is provided with a 70 screw threaded stem n . The table N is provided with die-holes n' of various sizes, and it may be turned around and slid about so as to bring any desired die-hole under the punch. A nut P is screwed upon the stem 75 n , and is provided with a notched operating-wheel p .

R is a lever journaled on the nut P and provided with a retractable catch p' for engaging with the notches of the operating- 80 wheel.

This punching machine is very useful in jobbing shops, as the punches can be changed very quickly so as to adapt the machine to a great variety of work. It is simply 85 constructed, is very strong and stiff, and is not liable to get out of order.

What I claim is:

1. In a punching-machine, the combination, with a frame comprising three parallel 90 bars, the two outer bars being longer than the center bar and provided with projections at their upper ends, of means for operating the punch carried by the said projections, a bracket and a guide each having forked end 95 portions inserted between the said outer bars and the center bar, fastening devices securing the said end portions to the said bars, a punch slidable in the said guide, and a die-block carried by the said bracket.

100

2. In a punching machine, the combination, with a frame provided with a guide of a crankshaft journaled in the said frame, arms secured to the said crankshaft and

provided with notched quadrant-plates, a lever pivoted between the said arms, a retractable catch carried by the said lever and connecting it to the said quadrant-plates, a punch having a stem which slides in the said guide, and a connecting-bar between the said crank-shaft and the stem of the said punch.

In testimony whereof I have affixed my signature in the presence of two witnesses.

AUGUST HOLMGREN.
